(57) **CLAIM**

The ornamental design for a hiccup remedy device as shown and described.

DESCRIPTION

FIG. 1 is a left side view of the invented hiccup remedy device in a state of use.

FIG. 2 is a front view of a hiccup remedy device;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a top, left, front perspective view thereof.

The head shown in broken lines in the drawings illustrates environmental subject matter and forms no part of the claimed design.
